UNITED STATES PATENT OFFICE.

WILLIAM D. WATSON AND ORLA H. IMAN, OF CHICAGO, ILLINOIS, ASSIGNORS, BY MESNE ASSIGNMENTS, TO WATSON SOLAR WINDOW COMPANY, OF CARMEL, NEW YORK, A CORPORATION OF NEW YORK.

METAL-FRAME WINDOW.

1,132,233.

Specification of Letters Patent.

Patented Mar. 16, 1915.

Application filed May 11, 1911. Serial No. 626,410.

To all whom it may concern:

Be it known that we, WILLIAM D. WATSON and ORLA H. IMAN, both citizens of the United States, residing at Chicago, in the county of Cook and State of Illinois, have invented certain new and useful Improvements in Metal-Frame Windows, of which the following is a specification.

This invention relates to improvements in metal frame windows, and has reference more particularly to improvements in that type of window which has come to be known to the trade as the "fenestra type."

Among the salient objects of the invention are to provide a construction in which the transoms and muntins are of sheet metal, as distinguished from solid metal, but are nevertheless of such form and construction as to afford the requisite strength combined with the advantages of sheet metal construction; to provide a construction in which is embodied a two-part separable muntin-bar, one of the halves of which is fixed or stationary and the other removable, and these parts of such construction that when properly united they afford enormous strength, are adapted to accommodate various thicknesses of glazing, and permit the glazing to be inserted and seated in structurally formed grooves in accordance with a general method practiced in this art; to provide a construction in which there are combined with the separable muntins cross-bars or transoms at right-angles to the muntins which are removable and may be set into place progressively as the glazing is inserted and serve to unite the proximate edges of the panes of glass in a simple, strong and extremely effective manner, and which at the same time cover a minimum area of the glass; and to provide an improved form of window construction which lends itself readily to modifications in size by the simple addition of more units.

Our invention, its novel constructional features, its manner of assembling, and the advantages inhering therein will all be readily understood when considered in connection with the accompanying drawings which illustrate one practical embodiment thereof, and in which—

Figure 1 is a side elevation, broken off at one side, of our improved window. Fig. 2 is a considerably enlarged vertical cross-section of the same, broken out between adja-

cent transoms. Fig. 3 is an enlarged central 55 vertical section transversely of the window-frame through one of the muntins of the upper half of the window-frame, the same being broken out between its ends. Fig. 4 is an enlarged detail view in horizontal section 60 through one of the muntin-bars, on the line 4—4 of Fig. 3. Fig. 5 is a detail view in vertical section through the joint between one of the permanent muntin-bars and the upper cross-bar of the jamb frame, as the same 65 would appear on the line 5—5 of Fig. 3. Fig. 6 is an enlarged detail view, in perspective, illustrating a structural feature of the upper and intermediate cross-bars and the manner of inserting the removable muntin- 70 bars and the panes of glass. Fig. 7 is a top plan view of the upper cross-bar of the outer frame or jamb. Fig. 8 is a perspective view of one of the continuous two-part muntin-bars and two of the continuous transom-bars, 75 showing a portion of the glass in place.

Referring to the drawings, 10 designates the vertical and 11 and 12 the upper and lower horizontal members, respectively, of a rectangular jamb frame adapted to be permanently set in the wall of a building. The members 10, 11 and 12 are hollow sheet-metal structures provided on their inner sides with grooves or channels, such as 11^a and 12^a adapted to seat the outer marginal 85 portions of the glazing. The structure herein shown also includes a central cross-bar 13 preferably formed, as best shown in Fig. 2, by a mating-bar or bars, such as the upper jamb bars 11, set edge to edge, and united 90 by internal cleats 14 secured to said bars as by screws 14^a; said intermediate cross-bar 13 being provided in its upper and lower sides with integral reentrant portions forming glass-receiving channels or grooves 13 and 95 13^b. The transverse frame bar 13 thus divides the entire structure into a pair of upper and lower duplicate sections. The sections thus formed are each subdivided by muntins and transoms into a plurality of 100 glazed panels depending, of course, upon the number of muntins and transoms employed, which latter is, of course, optional, and immaterial to the structural features involved in the present invention. We have herein 105 shown each section as employing a pair of transoms and a pair of muntins, thus creating in each section nine glazed panels. The

transoms, designated 15 are, as best shown in the sectional views, of Figs. 2 and 3, of H-shape in cross-section, being formed of sheet-metal pressed to the specified form; and the 5 ends of these transoms simply enter the vertical glass-receiving grooves formed in the inner sides of the vertical hollow jambs 10.

The muntins are of hollow sheet-metal construction, and each is a two-part structure comprising an outer permanent section 16 and a similar inner removable section 17 (Fig. 4). These sections preferably have the cross-sectional form illustrated in Figs. 4 and 7. The outer sections 16 are permanently secured at their upper and lower ends in the cross-bars 11, 12, and 13 of the main frame; while the inner sections 17 are removably secured at their ends in said cross-bars, for which purpose the latter are provided with openings, such as that shown at 20 18, in Fig. 6, of the cross-sectional form and dimensions of the muntin-bar 17, through which the ends of the latter may be readily inserted and withdrawn. The upper and 25 lower ends of the permanent muntin-bars 16 may be simply and strongly secured in place by splaying or spreading the inserted ends of said bars in the manner clearly shown at 16^a in Fig. 5.

30 Where the muntins between the cross-bars in which they are secured at their ends are of considerable length, it is desirable to provide intermediate connecting devices between the outer and inner bars of each pair; 35 and for this purpose we employ directly beneath each of the transoms 15 a connecting link 19 (Figs. 3 and 4), which is pivoted at 19^a between the side walls of the muntin-bar 16 and, at its free end, extends across 40 between the side walls of the muntin-bar 17, being provided at its free end with a slot 20 adapted to receive a bolt 21 passed through said slot and also through 45 slots 22 in the sides of the muntin bars 17. Lying in said slot on the outer side of the bolt 21 is a wedge 23 that is forced inwardly by the nut 24 of the bolt 21, which wedge, by bearing against the outer end of the slot 20, has the effect of automatically 50 forcing the removable muntin bars 17 into snug engagement with the adjacent side of the transom 15, thus clamping the latter snugly upon the edge of the glazing.

55 In assembling the window in the outer or bounding jamb frame, the permanent muntin bars 16 are first secured in place, after which the lower row of panes of glass 26 are set in proper position engaging the channels of the uprights 10 and lower cross-bar 12. The lower transom 15 is then put in place, the ends thereof entering the channels in the uprights 10. The next horizontal row of panes of glass is similarly set in place, followed by the next cross-bar or transom 60 15. The upper row of panes of glass is then

positioned by inserting the upper edge of the first pane through a slot 27 in the base of the lower channel of the central cross-bar 13 (see Fig. 2), then lowering the pane into the upper channel of the transom 15, 70 and then sliding it to one side or the other to fill one of the outer side panels. The second pane is similarly introduced and slid to the opposite side, while the third pane occupies the intermediate panel. In the same way the 75 several panes of glass filling the panels of the upper section are successively introduced, the upper cross-bar 11 of the jamb frame having a slot 28 (Fig. 7) similar to and for the same purpose as the slot 27. 80 The several removable muntin bars 17 are then inserted in the manner shown in Fig. 3 by first introducing their upper ends through the openings 18 in the upper and intermediate cross-bars 11 and 13, respectively, then swinging their lower ends inwardly and dropping them through similar openings in the upper sides of the cross-bars 13 and 12, said lower ends being stepped on 85 rests 25 secured within said cross-bars, as clearly shown in Figs. 2 and 3. The connecting links 19, when employed, are swung downwardly from the dotted line position (Fig. 3) to the horizontal position just prior to the introduction of each of the transoms 90 15; and after the insertion of the removable muntin-bars 17, they are connected to the latter by the bolts 21 (and wedges 23, when employed), whereby the several parts of the 95 complete window are united into a strong and rigid structure. The purpose of pivoting the connecting links 19 is to be able to swing said links upwardly out of the way when inserting the end panels of each horizontal row, these panels being inserted at 100 the central opening and slid edgewise to permanent position.

105 The edges of the glazing panels which are engaged by the H-shaped transom bars are snugly held by the latter, especially where said transom bars are formed, as herein shown, of sheet metal folded and pressed to shape, since they are to a certain extent compressible upon the glazing by the connecting 110 and tightening links which unite the outer and inner muntin bars. The other edges of the glazing panels have a more or less loose engagement when first inserted with the 115 channels formed in the muntins and side and cross-bars of the jamb-frame; and tight joints at these points may readily be secured by a packing of putty, paint, or other suitable material, as indicated at 29 and as is well understood in the art.

120 We claim—

1. In a sheet metal window construction, the combination of a jamb-frame, a continuous two-part muntin member, and a continuous transom bar uniform in cross section 125 throughout its length, passing between, 130

without intersecting, the parts of said vertical muntin member, one of the parts of said muntin member being removable.

2. In a sheet metal window construction, 5 the combination of a jamb-frame, a continuous muntin member comprising two parts having uniform cross-section throughout their length, said parts having opposed spaced flat surfaces for admitting the glazing, and a continuous transom bar uniform 10 in cross-section throughout its length, passing between but not intersecting the parts of said vertical muntin member, one of the parts of said muntin member being removable.

3. In a sheet metal window construction, the combination with a jamb-frame, of a continuous two-part vertical muntin member, and a continuous H-shaped transom-bar passing 20 between, without intersecting the parts of said vertical muntin member, one of the parts of said muntin member being removable.

4. In a sheet metal window construction, 25 the combination with a jamb-frame, of a sheet metal transom of H-form in cross-section, a two-part muntin comprising a muntin bar permanently secured at its ends in the upper and lower cross-bars of the jamb-

frame and crossing one side of said transom, and a companion muntin bar removably secured at its ends in the upper and lower cross-bars of the jamb-frame and crossing the opposite side of said transom, and a detachable connector between said 30 35 muntin bars, substantially as described.

5. In a sheet metal window construction, the combination with a jamb-frame, of a sheet metal transom of H-form in cross-section, a two-part muntin comprising a hollow 40 sheet metal muntin bar permanently secured at its ends in the upper and lower cross-bars of the jamb-frame and crossing one side of said transom, and a companion hollow sheet metal muntin bar removably 45 secured at its ends in the upper and lower cross-bars of the jamb-frame and crossing the opposite side of said transom, and a connecting link pivoted at one end within said 50 permanently secured muntin bar and separably attached at its other end within said removably secured muntin bar, substantially as described.
